Howard S. Barlow

ATTORNEY

UNITED STATES PATENT OFFICE.

NILS G. LARSON, OF ATTLEBORO, MASSACHUSETTS.

WRENCH.

1,419,391.

Specification of Letters Patent. Patented June 13, 1922.

Application filed February 19, 1920. Serial No. 360,016.

To all whom it may concern:

Be it known that I, NILS G. LARSON, a citizen of the United States, and resident of the city of Attleboro, in the county of 5 Bristol and State of Massachusetts, have invented certain new and useful Improvements in Wrenches, of which the following is a specification.

This invention relates to ratchet wrenches, 10 and has for its object to provide an improved form of such a wrench which is of simple and practical construction that may be manufactured at the minimum expense and produced rapidly by automatic 15 machinery.

The nature and advantages of this invention will be better understood when the following detail description is taken in connection with the accompanying drawings, 20 the invention residing in the combination and arrangement of parts as claimed.

In the drawings forming part of this specification like numerals of reference indicate similar parts in the several views and 25 wherein:—

Figure 1 is a side elevation partly in section of my improved wrench with one of the side plates of the head, removed.

Figure 2 is a detail perspective view of 30 the ratchet pawl.

Figure 3 is a perspective view of the hub member, showing the pawl mounted therein.

Figure 4 is a side elevation showing the toothed head with the hub removed and 35 showing a portion of the wrench handle.

Figure 5 is a section on line 5—5 of Figure 1, through the head portion, showing the hub-retaining side plates and the pawl-receiving bore in the periphery of the hub.

40 Figure 6 is an edge view showing the general shape of the handle and head with the side plates on the head for retaining the hub in position therein.

Figure 7 is the same as Figure 5 with the 45 exception that the side plates instead of being held by rivets are retained by the spreading edges of the shouldered portions of the hub, extending over those of the side plates for the purpose of retaining the hub 50 in operative position in the head.

With reference to the drawings, 10 designates the handle portion of my improved wrench and 11 the head portion thereof all being cut from a single piece of sheet 55 stock. This head portion is preferably made in circular form and is provided with

a central, circular opening 12 having inwardly-projecting teeth 13, the points 14 of which are preferably flattened slightly to provide bearings on which the hub member 15 is adapted to rotate.

It will be seen by this construction that the handle and the head and the toothed, central opening in the head are so shaped as to be formed by a punching or cutting 65 process.

The hub member 15 is preferably in the form of a circular disk having laterally-extending shoulders 16 formed on its opposite side faces, the whole being adapted to 70 be constructed by automatic machinery such as the so-called screw-machine or the like, the center hole 17 which is usually formed square is preferably broached out to the desired size for the reception of the shanks 75 of the socket portions of the wrench (not shown).

Into the peripheral surface of this head member I preferably drill a hole 18 whose axis is substantially parallel with one of 80 the side walls of the center hole 17, see Figure 1, and I may provide one or more pawl members 19 which are preferably provided with a cylindrically-shaped body portion flattened at 20 to engage the side face 85 of each of the teeth 13 as the hub rotates. The inner end 21 of this cylindrical pawl is preferably turned down to receive the coils of the operating spring 22, which spring serves to force the pawl upwardly 90 causing its outer end 23 to abut against one edge of the teeth 13.

On opposite sides of the head portion of this wrench I secure the thin side plates 24 for the purpose of holding the hub member 95 in operative position in the head.

In some cases I secure these plates by means of rivets 25, while in other cases I bevel the inner edges 26 of these plates as shown in Figure 7, and then turn the 100 outer edges 27 of the shoulders 16 upwardly over these beveled edges 26, thereby binding these plates to the hub member to turn therewith thus doing away with the rivets 25 above referred to.

105 My improved wrench has many structural advantages over other wrenches of this character among others being first, that the handle and head portion are of the same thickness and may be readily cut or blanked 110 from sheet stock all in a single punching operation thus reducing the cost of con-

structing this member to the minimum; second, the hub member is constructed in a circular disk form having laterally-extending, integral shouldered portions thus giving the maximum width to the disk for the reception of the shank portion of the socket wrenches, which are operated in the usual way by the rotation of this hub member; third, this hub member is retained in position by thin plates or collars positioned on either side of the head portion of the wrench and are either secured to the head portion of the wrench itself as illustrated in Figures 1 and 5, or these plates may be secured to the shoulder portions of the hub in the manner illustrated in Figure 7, either of which arrangements reduces the cost of construction to the very minimum and at the same time obtains the maximum strength of a wrench of this character; fourth, a hole 18 is drilled or formed into the periphery of the hub member which may be done by a simple drilling operation and a pawl is operatively mounted in this hole in such a manner that the wall of the hole serves to support the pawl against a crushing, working strain by which construction this pawl is adapted to carry the greatest load that can be exerted upon the wrench.

While I have shown and described what

I consider the preferred embodiment of the invention, I desire it understood that I do not limit myself in this connection and that such changes may be resorted to when desired as fall within the scope of the appended claim.

I claim:

A ratchet wrench comprising a handle having a head portion with an annular opening through it provided with inwardly-projecting teeth with flat top bearing ends, a hub member rotatably mounted in said opening receiving a working bearing on the flattened portion of said teeth and having laterally-extending bearing hub portions on its opposite faces and said members having a cylindrical peripheral bore whose axis describes the chord of an arc, and a spring-pressed pawl having a substantially cylindrical body portion endways slidable in said bore, said pawl having a flattened tooth-engaging surface and its body being supported by the walls of its bore against a laterally crushing working strain, and bearing plates fixedly secured to both sides of said head-portion fitted to engage and assist in supporting said bearing hub portions in operative position in said head.

In testimony whereof I affix my signature.

NILS G. LARSON.
